UNITED STATES PATENT OFFICE.

PAUL AIMÉ TREPIER, OF PARIS, FRANCE.

METAL WHEEL FOR VEHICLES.

1,405,358.

Specification of Letters Patent. Patented Jan. 31, 1922.

Application filed March 31, 1920. Serial No. 370,312.

To all whom it may concern:

Be it known that PAUL AIMÉ TREPIER, residing in Paris 11, Rue Dupont de l'Eure, France, have invented new and useful Improvements in or Relating to Metal Wheels for Vehicles, of which the following is a specification.

This invention relates to those metal wheels for vehicles, in which the core of the wheel is constituted by a sheet metal disc connected at its centre to a hub, and at its circumference to a rim. These wheels offer a smaller resistance close to the hub, and it is there that the risk of becoming deformed under the action of shocks or of lateral stresses is apparent.

This invention comprises strengthening the central portion of a wheel as above described by means of a second disc of a smaller diameter than that of the first one, this second disc being secured to the hub, so that the wheel can be made detachable by separating the two discs.

In the accompanying drawings,

Figure 1 is a cross-section of a single wheel according to this invention,

Figure 2 is a front elevation of the same wheel, the left hand portion showing the wheel fitted up, whilst from the right hand portion the detachable disc is removed.

Figure 3 is a cross-section of a two-rim wheel, and

Figure 4 is a partial view, similar to that of Figures 1 and 3, of a modified construction of the disc.

The wheel (Figures 1 and 2) is constituted by a fixed central disc 2 and a detachable disc 1. The disc 2 is secured to the hub 3 and to the said disc are permanently secured the fixing bolts 6 and the strengthening plates 10 which are welded or riveted. The disc 1 is secured to the rim and centered on the hub 3. It is provided with holes for the passage of the bolts 6 and each hole is strengthened by a washer 7 welded or riveted. The disc 2 is stiffened by a flange 5, on the circumstance of which is mounted the disc 1 and recesses are provided in the latter for the passage of the washers 7. The fixing is done by means of nuts 8.

When assembling, the disc 1 is first

mounted on the shoulder 9 of the hub 3, the tightening of the nuts then bend it so as to bring it into contact with the flange 5, and then, at each bolt, with the plates 10. The result is that the disc 1 is firmly pressed against the disc 2 and resists any lateral shocks well.

The twin rim wheel (Figure 3) is constituted by two detachable discs 1 and 1' arranged back to back and connected to one and the same central disc 2 secured to the hub 3. The fixing is the same for both being done by means of bolts 6 and nuts 8. The disc 1' is pressed against the shoulder 9 and the flange 5 as in Figure 1. The disc 1 is in contact with the disc 1' at its central portion, and the three discs are firmly pressed against each other. Circular corrugations 11 stiffen the sheet metal between the bolts.

In Figure 4, a flange 5' is provided upon the central disc against which is pressed the disc 1, the flange 5' being continued by a cylindrical portion 12 intended to form a brake drum.

What I claim as my invention and desire to secure by Letters Patent is:

1. A vehicle wheel comprising two discs of unequal sizes connected together by bolts, the larger one being secured to a rim, whilst the smaller one, secured to the hub, rests at its outer circumference against the larger one.

2. A detachable vehicle wheel comprising two discs of unequal size and bolts connected to them, the larger disc being secured to a rim, whilst the smaller disc, secured to the hub, rests at its outer circumference against the former, the wheel being detached by separating the two discs.

3. A detachable twin vehicle wheel comprising two discs, each secured to a rim, arranged back to back and connected by bolts to a third smaller disc secured to the hub, the three discs resting against each other around the circumference of the small disc, the wheel being detached by separating the three discs.

4. A detachable vehicle wheel, comprising unequal discs connected together by bolts, the large disc being secured to the rim, whilst the smaller one, secured to the

hub, is arranged so as to form a brake drum, the wheel being detached by separating the discs.

5. A vehicle wheel comprising a plurality of connected metal plates, one of said plates being dished inwardly and the other of the said plates being dished outwardly, and a brake drum integral with the last mentioned plate.

6. A vehicle wheel comprising a plurality of connected metal plates, said plates being dished oppositely to each other, one of said plates having an integral seat for the tire rim and the other of said plates having an integral brake drum, and means for securing said plates together. 15

PAUL AIMÉ TREPIER.
